UNITED STATES PATENT OFFICE.

SAMUEL HAYWARD, OF BOSTON, MASSACHUSETTS, ASSIGNOR TO J. ESTEY & CO., OF BRATTLEBOROUGH, VERMONT.

DESIGN FOR REED-ORGAN CASES.

Specification forming part of Design No. 7,842, dated November 3, 1874; application filed September 14, 1874.
[Term of Patent 14 years.]

CASE B.

To all whom it may concern:

Be it known that I, SAMUEL HAYWARD, of Boston, Massachusetts, have invented a Design for an Organ-Case, and assigned to J. ESTEY & Co., of Brattleborough, Vermont, of which the following is a specification:

In the accompanying photograph, to which reference is made, the nature of my design is fully illustrated; and it relates to the end handles, the front corners of the case, and to the front board.

Upon each end of the case, and near the center thereof, are the handles *a*, which are formed in the shape of a cross, the horizontal bar being connected with knobs or short brackets projecting from each side of the case, and the vertical bar resting on a short arm or bracket projecting from about the center of the case, and joined therewith by a rosette, preferably, as shown. The horizontal bar of the cross is cylindrical on each end, and cubical at the intersection of the vertical bar. The upper part of the vertical bar is surmounted by a hemispherical cap, and the lower part tapered downwardly and terminated by a band and a truncated cone, which rest on the cubical end of the supporting-bracket. This form of handle gives the case a unique appearance, while the combination of the curved, angular, and flat forms, in the ornamentation of the handle, renders the same very pleasing to the eye. I do not, however, wish to confine myself to this special ornamentation, as other ornamentation may be used without departing from the nature of my design, which consists chiefly in forming the handle in the shape of a cross.

The front corners of the case are composed of consoles *c c*, which rest on the projecting corners of the base, and extend upward about

one-third the distance toward the key-board portion of the instrument, where they unite with the pillars *d d*, which extend to and support the corners of the projecting portion of the case. The centers of the pillars are in form that of truncated cones, and their sides are grooved and otherwise ornamented, as shown. This conical form of the pillar, together with the graceful curve of the console, has a very pleasing effect, and adds greatly to the beauty of the case.

Upon the front board of the case, an oblong panel, *e*, is formed, and superposed upon the center of this is an oval or circular tablet or panel, *b*, which is wider than the panel *e*, and extends beyond the sides thereof, as shown. These panels impart to the front of the case an appearance of relief and finish, while, being simple in design, they do not subdue or detract from the ornamental effect of the corners *d c*.

I claim as my invention—

1. The design for an organ-case, composed of the handles in the shape of a cross, substantially as shown and described.
2. The design for the front corners of an organ-case, formed of the consoles *c c*, and the conical pillars *d d*, substantially as shown and described.
3. The design for the front board of an organ-case, formed of the oval or circular panel *b*, supported upon the center of an oblong panel, *e*, substantially as shown and described.

In testimony whereof I have hereunto signed my name in the presence of two subscribing witnesses.

SAMUEL HAYWARD.
